UNITED STATES PATENT OFFICE.

MARCUS DATTLEBAUM, OF OAKLAND, CALIFORNIA.

STRAP CONNECTION FOR GARMENTS OR THE LIKE.

SPECIFICATION forming part of Letters Patent No. 712,363, dated October 28, 1902.

Application filed March 4, 1902. Serial No. 96,650. (No model.)

To all whom it may concern:

Be it known that I, MARCUS DATTLEBAUM, a citizen of the United States, residing at Oakland, county of Alameda, State of California, 5 have invented an Improvement in Strap Connections for Garments or the Like; and I hereby declare the following to be a full, clear, and exact description of the same.

My invention relates to a device which is 10 especially designed for making connections for straps such as are used upon trousers, vests, and wearing-apparel and is also applicable for making connections wherever buckles are used.

15 It consists of a plate having a plurality of studs projecting from its face and adapted to pass through openings or holes made in the parts to be connected, these studs having heads to retain them and the plate in place.

20 The straps to be connected are formed with suitable holes, so that one of the studs may be entered into one strap and the other into the one with which it is to be connected, and any adjustment is thus easily made.

25 Referring to the accompanying drawings, Figure 1 shows the application of my strap connection. Fig. 2 shows the strap connection with one of the straps disconnected. Fig. 3 is a perspective view of the plate. Fig. 4 30 is an edge view of Fig. 1.

35 For the purpose of connecting the adjusting-straps such as are used upon the backs of trousers, vests, and various undergarments it is customary to employ buckles, one end of which is permanently secured to one of the straps, and the other strap is adapted to pass through the opening in the buckle and be engaged by the usual teeth or points. This attachment is objectionable, first, because any considerable taking up of the strap 40 carries the buckle far to one side of the center; secondly, because the teeth of the buckle soon wear out the strap through which they pass, and, besides, being objectionable on account of the projecting points.

45 In my invention the straps A and B have buttonholes made in them, as at 2. There may be as many of these holes in line as the

probable amount of adjustment will require, and when made in ordinary woven fabric the 50 buttonholes will preferably be worked around the edges, so as to give them strength and permanence.

3 is a metal or other rigid plate which may be made in any suitable or desired shape. I 55 have here shown the plate as made rectangular and open in the center, thus forming narrow surrounding sides of sufficient strength for the purpose. Upon each of the sides of this plate are studs projecting therefrom and having heads upon them, as at 4. I have here shown the studs as having their inner ends fixed in curved projections 5, formed upon the outer edges of the longer sides of the bars or plate, so that the studs 60 are separated by a little more than the width of the plate.

In applying the device one of the ends of the strap, as A, is passed through the opening in the plate 3, and one of the holes 2 is 70 passed over the stud which projects from the bar on that side. The other strap B is then brought over the other stud and is in like manner attached thereto, so that the contiguous ends of the two straps cross each other 75 an equal distance upon each side of the securing device, which always remains in the center. For the longest adjustment the studs may be placed in the holes nearest the outer ends of the straps. A second adjustment 80 may be made by taking up one of the straps to the second hole, a third adjustment by taking up the other strap to the second hole, and so on, as far as may be found necessary.

This device is equally applicable to straps 85 used upon harness, and for other purposes where buckles are usually employed it forms a neat finish and avoids the objection to buckles having tongues.

Having thus described my invention, what 90 I claim, and desire to secure by Letters Patent, is—

1. A device for connecting straps consisting of a thin flat plate the sides and ends of which lie substantially in the same plane said 95 plate having a stud projecting from each of

two of its parallel sides and extending in the same direction and from the same face of the plate.

2. A connecting device for straps consisting of an open centered plate through which the free end of one of the straps is passed, a headed stud projecting from the outer edge of the plate, one of said straps having a hole through which said stud is passed, a second

headed stud projecting from the opposite to edge of the plate the second straps having holes therein adapted to fit over said stud.

In witness whereof I have hereunto set my hand.

MARCUS DATTLEBAUM.
